COMBINED LAMP SOCKET AND PLUG

Rob Roy Glass, Rome City, Ind., assignor to
Lyall Electric, Inc., Albion, Ind.

Filed Oct. 22, 1975, Ser. No. 624,945

Term of patent 14 years

Int. Cl. D26—99

U.S. Cl. D26—1 G

FIG. 1

FIG. 2

FIG. 3

FIG. 4

FIG. 5

FIG. 1 is an end view of a combined lamp socket and plug showing my new design;

FIG. 2 is a side view thereof;

FIG. 3 is an end view thereof as seen from the right of FIG. 2 and is the end opposite the end shown in FIG. 1;

FIG. 4 is a top view thereof; and

FIG. 5 is a bottom view thereof.

The side opposite that represented in FIG. 2 is substantially identical to that shown.

I claim:

The ornamental design for a combined lamp socket and plug, substantially as shown and described.
